REFRIGERATOR CAR

Garth G. Gilpin, Riverside, Ill., assignor to Standard Railway Equipment Manufacturing Company, Chicago, Ill., a corporation of Delaware

Application August 1, 1938, Serial No. 222,363

13 Claims. (Cl. 62—17)

This invention relates to refrigerator cars used to transport perishable commodities at a temperature within a predetermined range. This necessitates use of a cooling means in summer 5 and a heating means in winter.

A refrigerator car comprises insulated walls, roof and floor and, when used in warm weather, a means for cooling the air as it circulates about the car. The cooling means may be fresh water ice, a mixture of ice and salt, a brine solution comprising ice, water and salt, or a eutectic ice consisting of frozen brine. The cooling means may be placed at the ends of the car and separated by bulkheads from the lading compartment or may be suspended immediately below the ceiling.

This invention applies particularly to cars in which there are preferably a plurality of refrigerant containers near the roof. These containers 20 may have foraminous walls through which air may circulate when the refrigerant is ice or ice and salt. The containers may also be solid tanks when brine is used, or they may have their upper walls foraminous to facilitate air circulation and their lower walls and bottom solid for partial retention of brine. A drip pan or partition is provided below each container to catch and drain the melted ice and condensation from the container. A flue is preferably 25 provided to communicate between the passage above the drip pan and the space between the floor rack and the floor. The flue serves as a path for the downward movement of air which has been cooled by the refrigerant.

It is an object of this invention to hinge the bottoms of the refrigerant containers to the containers and also to provide latches or other means for securing said bottoms to the containers. The latches may be easily released to 30 allow the bottoms to swing downwardly. It is a further object of the invention to hinge and latch the drip pans in a similar way. The purposes and advantages of this construction are as follows:

When a refrigerator car arrives at its destination there is usually a quantity of ice remaining in the containers. This is undesirable because it constitutes an unnecessary load which must be hauled on the return trip. It is sometimes desired to re-ice the car immediately and any residual ice would be disadvantageous, particularly if the containers are brine tanks. For these reasons the container bottoms and the subjacent drip pans are made removable for removal of ice remaining in the containers.

A further object of the invention is to hinge only parts of the bottoms of the containers. A large amount of ice is carried in refrigerator cars and the containers must be strong and, therefore, heavy to support the weight. Furthermore, there may be a considerable quantity of ice remaining in a container. This weight might be too great for one man, or even two men, to handle safely if it is necessary to operate the entire bottom as a unit. It is an object of this 10 invention to construct part of the bottom rigid with the container and hinge the remainder; then ice resting on the rigid portion may be pushed through the opening created by the removal of the hinged partition. It is another 15 object to further decrease the weight to be handled by hinging only a part of the drip pan and constructing the remainder rigid with the car.

Another advantage in hinging only a part of 20 the bottom of the container is the safety requirement. Very frequently a large amount of ice remains in a container and if the bottom is suddenly released, persons inside the car would be liable to injury by the resultant avalanche of 25 ice. However, if only a part of the bottom is released, the quantity of ice falling inside the car is materially less. The remaining ice can then be pushed from the rigid part of the bottom through the opening in small quantities. 30

It is frequently necessary to clean the containers of a refrigerator car because accumulated dirt may cause odors injurious to certain types of lading. It is an object of this invention to hinge the container bottoms and drip 35 pans, thus making the containers easily accessible for cleaning.

Refrigerant containers are frequently in need of repairs. Damage may be caused by dropping large amounts of ice into the containers from a great height by the shifting of the ice during service movements of the car, or by the corrosive action of salt which is frequently added to the ice to produce a lower temperature. A further object of the invention is to facilitate repairs 40 to the tank by hinging the container bottom and drip pan as heretofore described.

Another object of the invention is to make the drip pan accessible for cleaning by hinging it to the car structure.

Certain types of commodities require no refrigeration during transportation, but require ventilation. This is necessary because they emit a continuous supply of heat which must be carried away or the lading will become so warm 50 55

that it will be injured. Ventilation is ordinarily supplied by opening some or all of the hatch covers. It is an object of this invention to hinge the drip pan, thus providing a direct path for the ventilating air to reach the lading compartment. It is a further object to provide an adjustable support for the drip pan so that the amount of air entering the lading compartment may be controlled.

10 In the drawings:

Fig. 1 is a transverse section of a refrigerator car having foraminous refrigerant containers. The section is on line 1—1 of Fig. 5 and shows the container bottom in the closed position on the left and open position on the right.

15 Fig. 2 is a partial transverse section on line 2—2 of Fig. 5 showing the rigid portion of the bottom.

Fig. 3 is a fragmentary section showing a ventilating feature which may be used.

20 Fig. 4 is a horizontal section on line 4—4 of Fig. 5.

Fig. 5 is a vertical longitudinal section on line 5—5 of Figs. 1 and 2.

25 Fig. 6 is a partial transverse section of a car having tanks as refrigerant containers, showing the bottom closed on the left and open on the right.

Fig. 7 is a partial transverse section on line 30 7—7 of Fig. 8 showing the rigid portion of the bottom.

Fig. 8 is a vertical longitudinal section on line 3—3 of Figs. 6 and 7.

35 Figs. 9 and 10 show modified constructions.

In Figs. 1 and 2 the usual parts of a refrigerator car are shown, such as center sill 2; side sills 3; underframe cross members 4; sub-floor 5; floor 6; floor rack 7; side sheathing 8; side lining 9; auxiliary walls 10 providing the flues 11; side plates 12; outer roof sheets 13; running board 14; ceiling 15; hatch frames 16 surrounding the hatches 17; refrigerant containers 18; drip pans or partitions 19; upright walls 20 forming the duct 21 and insulation 22.

45 The foraminous refrigerant container 30 preferably comprises beams 31 extending between and secured to the side wall structure 29; foraminous sides 32 and a foraminous bottom 33 extend between and are supported by the beams 31. The beams 31 preferably consist of perforated webs 34 and upper and lower chords 35—36. The sides 32 may be wire mesh, expanded metal, perforated sheet, or other foraminous material.

55 The bottom 33 of the container 30 preferably comprises a plurality of inverted channel shaped parallel slats 40. The slats 41 near the center of the container, (i. e., under the hatch 17) are rigidly secured to and supported by the beams 42—43, said beams also serving as the lower chords of the sides 32. The slats 44 near the ends of the container 30 are secured to stringers 45 to form units 46 entirely separate from the remainder of the container. These units comprising slats 44 and stringers 45 are hinged to the beam 42 and releasably secured to the beam 43 by a latch 47 or other suitable means.

70 The latching means 47 shown in the drawings comprises a member 50 secured to the stringers 45 and an arm 51 pivotally mounted on the beam 43. The arm 51 has a projecting finger 52 and a downwardly disposed leg 53, said finger 52 engaging the member 50 to prevent downwardly swinging movement of the unit 46. A lug 54 mounted upon the partition 19 engages the leg

53 to prevent rotation of the arm 51 and, therefore, to prevent dropping of the unit 46 after the partition 19 has been raised to its upper horizontal position.

The upright walls 20 are shown secured to the beams 31 and extending between said beams. The partitions 19 are hinged at 57 to the auxiliary walls 10 and releasably secured by a suitable latching means 58 to the upright walls 20. The drawings show the partition 19 below the container 30 to be formed of three sections, each separately hinged and latched. Since only the end portions 59 must be lowered to remove the ice from the container, this arrangement reduces the weight which must be handled. If it is necessary to clean or repair the containers 30 the center portion 60 may be lowered.

The drawings illustrate only a short portion of the bottom at each end of the container hinged. Although there are other practical arrangements, the one shown is preferred because the weight to be handled is small and because it is a relatively simple operation to dump the ice remaining on the rigid part of the bottom. The operation consists of reaching through the hatch with a paddle or other instrument and pushing the ice toward the ends of the container where it falls through the openings left by the removal of the end parts of the bottom.

30 Fig. 3 shows an arrangement used for ventilation of the car. An adjustable means 61 substituted for the latch-like fastener 58 allows an opening 62 through which air may circulate to the lading compartment 63 when the cover is removed from the hatch 17.

35 Figs. 6—8 show a refrigerant container 70 adapted to the use of a liquid refrigerant, such as brine. The tank 70 is formed, preferably by welding, from imperforate metallic sheet, the bottom 71 having corrugations 72 to give it greater strength. A pipe 73 leads from the tank 70 to outside the car and is equipped with a valve which may be closed to insure retention of the brine.

40 In the case of the brine tank the center portion 45 of the bottom 71 under the hatch 17 is shown hinged and the ends 75 rigid. A gasket 76 made preferably of rubber or other pliable material is provided between the rigid portion 75 of the bottom and the hinged portion 74 at their overlapping edges. The hinge 77 is designed so that the distance between the hinge 74 and rigid portions 75 of the bottom may be adjusted. Then the surfaces bearing on the gasket 76 may be adjusted to keep the gasket compressed to an extent necessary to insure a watertight joint. The clamp 78 is adapted to exert a considerable pressure on the portion of the gasket 76 adjacent said clamp. Other clamps 79 spaced at intervals around the overlapping portions of the bottom 60 are used to keep the gasket 76 compressed at all points.

45 Fig. 9 shows a construction using a container having a solid bottom 84 to retain some brine and having foraminous upper walls 85. The advantages of this type of container are that it retains some brine which is necessary to produce a low temperature and that the foraminous top 85 allows free circulation and ventilation. The arrangement is similar to that shown in Fig. 1 70 except the hinged part of the bottom 84 has an upstanding flange 86 surrounding it. The flange 86 adds rigidity to the bottom 85 in addition to retaining brine.

50 Fig. 10 shows the bottom of the container 75

hinged at 90 to the side wall of the car. Any arrangement in which the part of the bottom 46 is hinged to any part of the car structure, such as refrigerant container or side wall, should be construed as being within the scope of the invention.

It is important that the hinge supporting the bottom of the container and the hinge supporting the portion 19 be arranged so that sufficient clearance is allowed for dropping the container bottom after the partition has been dropped. Also, when only part of the partition is to be dropped, it is important that the hinged part is of sufficient size to allow passage of the hinged part 15 of the container bottom through the opening created.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

25. 1. In a refrigerator car having spaced apart insulated walls, an insulated roof, and a hatch in said roof in combination with a refrigerant container below said hatch and arranged to be loaded therethrough, the bottom of said container being removably secured to said container, and a substantially horizontal partition below said container, said partition being hinged at one edge thereof to the car structure and releasably secured remote from the hinge.

35. 2. In a refrigerator car having spaced apart insulated walls, an insulated roof, and a hatch in said roof in combination with a refrigerant container below said hatch and arranged to be loaded therethrough, the bottom of said container being hinged at one edge thereof to the car structure and releasably secured remote from the hinge, and a substantially horizontal partition below said container, said partition being hinged at one edge thereof to the car structure and releasably secured remote from the hinge, said bottom and said partition being arranged to permit swingable movement of said bottom upon swingable movement of said partition.

40. 3. In a refrigerator car having spaced apart insulated walls, an insulated roof, and a hatch in said roof in combination with a refrigerant container below said hatch and arranged to be loaded therethrough, a part of the bottom of said container being rigid with said container and another part of the bottom of said container being hinged at one edge thereof to the car structure and releasably secured remote from the hinge, and a substantially horizontal partition below said container, the part of said partition below the hinged part of said bottom being hinged at one edge thereof to the car structure and releasably secured remote from the hinge, said bottom and said partition being arranged to permit swingable movement of the hinged part of said bottom upon swingable movement of the hinged part of said partition.

45. 4. In a refrigerator car having spaced apart insulated walls, an insulated roof, and a hatch in said roof in combination with a refrigerant container below said hatch and arranged to be loaded therethrough, the middle part of the bottom of said container being rigid with said container and the end parts of the bottom of said container being hinged at one edge thereof to the car structure and releasably secured remote

from the hinge, and a substantially horizontal partition below said container, the parts of said partition below the hinged parts of said bottom being hinged at one edge thereof to the car structure and releasably secured remote from the hinge, said bottom and said partition being arranged to permit swingable movement of the hinged parts of said bottom upon swingable movement of the hinged parts of said partition.

5. In a refrigerator car having spaced apart insulated walls, an insulated roof, and a hatch in said roof in combination with a refrigerant container below said hatch and arranged to be loaded therethrough, and a substantially horizontal partition below said container, a part of said partition being hinged at one edge thereof to the car structure and releasably secured remote from the hinge.

6. In a refrigerator having a roof and a substantially vertical wall, a hatch in the roof, a refrigerant container below said hatch and arranged to be loaded therethrough, said container being disposed adjacent the refrigerator wall, an upright wall adjacent said container and remote from said refrigerator wall, a substantially horizontal partition below said container, means associated with said refrigerator wall for hinging the bottom part of said container and means to releasably secure said partition against the lower edge of said upright wall.

7. In a refrigerator having a roof and a substantially vertical wall, a hatch in the roof, a refrigerant container below said hatch and arranged to be loaded therethrough, said container being disposed adjacent the refrigerator wall, an upright wall adjacent said container and remote from said refrigerator wall, a substantially horizontal partition below said container, means associated with said refrigerator wall for hinging the bottom part of said container and means to space said partition from said upright wall in adjustable relation thereto.

8. In a refrigerator having a hatch in the roof, a refrigerant container below said hatch and arranged to be loaded therethrough and a substantially horizontal partition below said container, the bottom of said container being removably secured thereto and said partition being removably secured to the refrigerator structure.

9. In a refrigerator car having spaced apart insulated walls, an insulated roof and a hatch in said roof in combination with a refrigerant container below said hatch and arranged to be loaded therethrough, the bottom of said container being hinged at one edge thereof to the car structure and releasably secured remote from the hinge and a substantially horizontal partition below said container, said partition being hinged at one edge thereof to the car structure and releasably secured remote from the hinge.

10. In a refrigerator car having a roof and a wall, a refrigerant container below the roof, a hatch in said roof communicating with the interior of said container for loading refrigerant into the container, an opening in the bottom of said container for removal of refrigerant therefrom, a closure for said opening, and a partition below said container, a part of said partition below said opening hinged for downward swinging movement.

11. In a refrigerator car having a roof and a wall, a refrigerant container below the roof, a hatch in said roof communicating with the interior of said container for loading refrigerant into the container, an opening in the bottom of

- said container for removal of refrigerant therefrom, a closure for said opening, and a partition below said container, a part of said partition below said opening being removable.
- 5 12. In a refrigerator car having a roof and a wall, a refrigerant container below the roof and adjacent said wall, a hatch in said roof communicating with the interior of said container for loading refrigerant into the container,
- 10 an upright wall on the opposite side of the container from the refrigerator wall, a partition below said container extending substantially between said upright wall and said refrigerator wall, means to hinge said partition to said re-

frigerator wall, and means to support said partition in adjustably spaced relation to said upright wall.

13. In a refrigerator having an insulated roof, a hatch in said roof and a refrigerant container below said hatch and arranged to be loaded therethrough, said container comprising a foraminous upper part and a lower part comprising an imperforate bottom provided with an upstanding peripheral flange, said lower part being hinged at one edge thereof to the car structure and releasably secured remote from the hinge.

GARTH G. GILPIN.
